US00D943980S

(12) **United States Design Patent** (10) **Patent No.:** **US D943,980 S**
(45) **Date of Patent:** **** Feb. 22, 2022**

(54) **SHOE**

(71) Applicant: **Reebok International Limited**, London (GB)

(72) Inventor: **Brian Rinella**, Canton, MA (US)

(73) Assignee: **Reebok International Limited**, London (GB)

(**) Term: **15 Years**

(21) Appl. No.: **29/778,464**

(22) Filed: **Apr. 13, 2021**

Related U.S. Application Data

(63) Continuation of application No. 29/693,931, filed on Jun. 6, 2019, now Pat. No. Des. 917,849.

CLAIM

The ornamental design for a shoe, as shown and described.

DESCRIPTION

FIG. 1 is a top front perspective view of a shoe showing the claimed design;

FIG. 2 is a left side view thereof;

FIG. 3 is a right side view thereof;

FIG. 4 is a front view thereof;

FIG. 5 is a rear view thereof;

FIG. 6 is a top view thereof; and,

FIG. 7 is a bottom view thereof.

The dashed broken lines in the figures show portions of the shoe that form no part of the claimed design.

The dot-dash broken lines in the figures show boundaries that form no part of the claimed design.

The oblique shade lines in the figures show transparency or translucency.

1 Claim, 7 Drawing Sheets
